UNITED STATES PATENT OFFICE.

DAVID SCHULER, OF KERRTOWN, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,108,252.

Specification of Letters Patent. Patented Aug. 25, 1914.

Application filed September 9, 1910. Serial No. 581,155.

To all whom it may concern:

Be it known that I, DAVID SCHULER, a resident of Kerrtown, in the county of Crawford and State of Pennsylvania, have invented a new and useful Improvement in Garment-Stays, of which the following is a specification.

This invention relates to stays for garments and the like and more particularly to 10 wire stays for corsets.

The object of the invention is to provide a stay for this purpose which will readily yield edgewise as well as sidewise, and which is perfectly elastic or resilient, which is 15 light yet sufficiently stiff to give support to the garment, and in which the bending stresses cannot be concentrated at any point or points, and thereby avoiding short bends with consequent crystallization and breakage.

20 In the accompanying drawing Figure 1 is an enlarged face view of a stay embodying the invention; Fig. 2 is an edge view of the same; and Fig. 3 is a cross section on the line 3—3, Fig. 1.

25 The stay is formed from wire, and in the embodiment illustrated is formed from a single wire only, although if desired it may be formed of a plurality of wires properly assembled. As shown, the wire is bent alternately back and forth to form a series of oppositely disposed eyes or loops 2 which are of the form illustrated and which crudely represents one form of an artist's palette. Each eye or loop has a broad outer end 5 with the wire extending in the direction of the length of the stay, thus forming substantially straight side edges therefor. The broad outer ends of the loops or eyes terminate in acute reverse bends 6, from which begin the straight portions of the crossings, said bends 6 being comparatively close to the side edges of the stay. The adjacent loops longitudinally of the stay overlap, that is to say, each loop or eye on one of its edges 40 is overlapped by the adjacent loop on that side of the stay, and on its opposite edge it overlaps the adjacent loop on that side of the stay. As a consequence, the loops or eyes are fairly broad at their outer ends, as shown. 45 The eyes or loops may be in contact at the points where they overlap, or merely in such close juxtaposition that they will contact when the stay is flexed abnormally. This

overlapping of the loops or eyes gives the stay when viewed edgewise a shingled appearance, as shown in Fig. 2. Consequently the loops can slide on each other when the stay is bent flatwise as well as when bent edgewise, but particularly when bent edgewise, thereby making the stay comparatively 55 flexible and particularly against edgewise bending. The result is that the stay will not twist or buckle as does a rigid flat structure when subjected to severe edgewise 60 stresses.

65 The transverse portions or crossings 4 are of curved or concave shape when the stay is viewed flatwise, as shown and all of them are curved in the same direction. This curved form distributes the stresses in such crossings when the stay is bent flatwise, such crossings acting partially by pure torsion or twisting due to their general transverse positions, but also being bent somewhat transversely of the wire due to the disposition of 70 portions of such crossings at an angle to a true transverse line. The consequence is that the stay possesses greater stiffness against 75 flatwise bending than would be the case if the crossings extended straight across, in 80 which latter event they would respond purely by torsion or twisting action when the stay is flexed flatwise. At the same time the curved form of these crossings gives a 85 longer length of wire in a given length of stay, thereby rendering the stay more flexible to edgewise bending stresses, and at the same time distributes the bending stresses over such a large area that crystallization and 90 breakage are practically entirely overcome. 95 It will also be noted from examination of Fig. 1 that each of the crossings from one side of the stay to the other is composed of a curved portion at one end thereof and a substantially straight portion at the other 100 end. As shown, the curved portion is overlapped by a substantial part of the straight portions of the next adjacent crossing in the direction of the length of the stay. For this reason and because of the fact that the 105 crossings are straight to some extent, upon flexing of the stay in a flatwise direction adjacent loops or eyes will contact and bear upon each other for a considerable distance along the length of the wire, thus preventing 110 the concentration of wear at a single point

- and rendering less likely the liability of adjacent loops to become displaced and snap out of proper position. The overlapping of the loops also has the effect of giving a mutual support or bracing effect from each loop to its neighbors when the stay is bent flatwise, so as to prevent short bending with the consequent crystallization and breakage, and also adds to the stiffness of the structure.
- 10 To further add to the stiffness of the structure, the crossings are deflected sidewise out of the flat plane of the stay, as shown in Fig. 3, thereby giving the stay as a whole a concave-convex form in cross section. This has the effect of rendering the stay as a whole stiffer, and making it stiffer against stresses tending to bend the same toward the convex side than when bent away from the convex side.
- 15 This particularly adapts the structure as a garment stay, where the stresses are almost entirely outwardly, so that by placing the stay with the concave face inwardly it most effectively takes care of the stresses to which it is normally subjected.
- 20 The stay described can be formed of comparatively light wire and is therefore of light weight, as well as being of open structure so that the garment is ventilative.
- 25

What I claim is:

A garment stay comprising wire bent back and forth to form two series of oppositely disposed, progressively arranged loops or eyes, said loops or eyes being substantially palette shaped with broad outer ends forming substantially straight side edges of the stay and terminating in acute reverse bends near the side edges thereof, the transverse portions or crossings being inclined and each having a straight portion beginning at one of said reverse bends near one edge of the stay and extending nearly to the other edge thereof and terminating in the curved broad outer end of a loop or eye on the other edge of the stay, the acute reverse bends at opposite edges of the stay all pointing in the same direction longitudinally thereof, and the straight portions of the crossings overlapping the curved portions of the next adjacent crossings and thereby distributing wear over a considerable length of wire.

In testimony whereof, I have hereunto set my hand.

DAVID SCHULER.
